Edgar V. L. S.

UNITED STATES PATENT OFFICE.

WILLIAM H. BASSINGER, OF PASSAIC, NEW JERSEY.

FILING-CABINET.

1,312,672.

Specification of Letters Patent.

Patented Aug. 12, 1919.

Application filed February 20, 1918. Serial No. 218,328.

To all whom it may concern:

Be it known that I, WILLIAM H. BASSINGER, a citizen of the United States, and residing at Passaic, in the county of Passaic and State of New Jersey, have invented 5 certain new and useful Improvements in Filing-Cabinets, of which the following is a specification, such as will enable those skilled in the art to which it appertains to 10 make and use the same.

This invention relates to filing cabinets or boxes, and the objects thereof is to provide an improved device of this class which is particularly designed for use in filing 15 photographic films or copies, but which may be also used for filing cards, pictures, bills, receipts or any other articles of the same class or form; a further object being to provide a filing device of the class specified, 20 comprising a rectangular box or case, the top and bottom or opposite sides of which are movable, said box or case being also provided with guide rods on which are mounted a pocket member or members having 25 pockets which open in opposite directions and which are exposed by moving or removing the top and bottom or opposite sides, whereby a box or case of predetermined dimensions is provided with the largest 30 possible number of pockets and the filing capacity thereof increased to the greatest possible extent.

The invention is fully disclosed in the following specification, of which the accompanying drawing forms a part, in which the separate parts of my improvement are designated by suitable reference characters in each of the views, and in which:—

Figure 1 is a plan view of a filing box 40 or case made according to my invention; Fig. 2 a section on the line 2—2 of Fig. 1; Fig. 3 a perspective view of one-half of one of a series of pocket sections which I may employ; and,

Fig. 4 a partial section on the line 4—4 of Fig. 1.

In the practice of my invention, as shown in the drawing, I provide a rectangular box or casing a composed of end members a^2 , 50 stationary side members a^3 and movable or removable side members a^4 , and for the purpose of this description the movable or removable side members a^4 will be called the top and bottom of the box or case.

Within the opposite ends a^2 of the box 55 or case and adjacent to said ends are placed parallel guide rods b , and these rods are mounted or secured in the sides a^3 in any desired manner and one or more of said rods may be employed at each end of the box 60 or case.

On the rods b are mounted pocket devices c which, in the form of construction shown, are composed of separate sections c^2 , a part of one of which is shown in perspective in 65 Fig. 3.

The pocket devices c or pocket sections c^2 are composed of oblong strips of strong tough paper or other suitable flexible material folded transversely to form loops c^3 70 which also form pockets c^4 which open in opposite directions and into which photographic films or other articles to be filed may be inserted from opposite sides of the box or case as will be readily understood. 75 Of course, the pockets c^4 which are available for filing purposes are those parts of the pocket devices or sections between the rods b or the eyelets or openings c^6 in the pocket devices or sections through which 80 said rods are passed, and, in practice, all of the pockets c^4 may be formed in or of a single long strip of material folded in the manner shown and described, or said pockets may consist of separate sections c^2 made 85 in the same manner and mounted on the rods b ; and when said pockets are all formed of one strip of material they may be numbered or indexed in the manner of other devices of this class, and when said pockets 90 are composed or made up of separate sections c^2 , the sections may be lettered or numbered, and the pockets in each section numbered or designated for filing purposes in the manner of other devices of this class 95 and, as will be understood an index card or direction card, or pamphlet may be provided giving directions as to the method of using the file box or case.

In the accompanying drawing the movable 100 opposite sides, or the top and bottom of the box or case, are made in the manner of ordinary slides having a tongue and groove connection with the stationary sides a^3 of the box or case, but said parts a^4 may be 105 hinged in position or otherwise movably connected with the body of the box or case, the only thing necessary in this construction

being that two opposite sides of the box or case be made movable so that said sides of the box or case may be opened, when desired, to afford access to the file pockets c^4 in the 5 pocket devices $c-c^2$.

With my improved file box or case photographic films or other articles to be filed may be inserted through opposite sides of the box or case into oppositely opening pockets, 10 and by forming the file pockets in the manner shown and described, I provide the greatest possible file space or capacity in proportion to the size of the box or case; and it will be understood that file boxes or cases 15 made in this manner may be of any desired dimensions, and said box or case may be used independently as filing cabinets, or a number thereof may be mounted in a suitable frame or cabinet casing, and while 20 I have shown and described the construction which I prefer in the construction of my improved file or file case, my invention is not limited to the details of construction herein shown and described, and changes 25 therein and modifications thereof may be made, within the scope of the appended claims, without departing from the spirit of my invention, or sacrificing its advantages.

Having fully described my invention, 30 what I claim as new and desire to secure by Letters Patent, is:—

- 35 1. A file box provided with opposite movable sides, the other opposite sides being stationary, guide rods fixed in said box and parallel with the ends thereof, and pocket devices mounted on said rods and movable longitudinally thereof and which open in opposite directions and in the direction of the movable sides.
- 40 2. A file box provided with opposite movable sides, the other opposite sides being stationary, guide rods fixed in said box and parallel with the ends thereof, and pocket devices mounted on said rods and movable 45 longitudinally thereof and which open in opposite directions and in the direction of the movable sides, said pocket devices being

composed of loops formed from a strip or strips of flexible material.

3. A file box of the class described, said 50 box being rectangular in form and provided with a movable top and a movable bottom, guide rods mounted in said box and adjacent to the opposite ends thereof, and pocket devices mounted on said guide rods and movable thereon and consisting of strips of flexible material folded transversely to form loops or pockets which open in opposite directions.

4. A file case of the class described, said 60 case being rectangular in form and provided with a movable top and a movable bottom, guide rods mounted in said case and adjacent to the opposite ends thereof, and pocket devices mounted on said guide rods and movable thereon and consisting of strips of flexible material folded transversely to form loops or pockets which open in opposite directions and which are composed of separate sections.

5. A file box provided with opposite movable sides, the other opposite sides being stationary, and means mounted in said box and movable longitudinally thereof for forming pockets which open in opposite directions and in the direction of the movable sides.

6. A file box provided with opposite movable sides, the other opposite sides being stationary, and means composed of flexible 80 material mounted in said box and movable longitudinally thereof and folded transversely to form pockets which open in opposite directions and in the direction of the movable sides.

In testimony that I claim the foregoing as my invention I have signed my name, in presence of the subscribing witnesses, this 18th day of February, 1918.

WILLIAM H. BASSINGER.
